UNITED STATES PATENT OFFICE

2,235,871

INTERNAL-COMBUSTION ENGINE

Eugene J. Farkas, Detroit, Mich., assignor to Ford Motor Company, Dearborn, Mich., a corporation of Delaware

Application December 8, 1939, Serial No. 308,131

11 Claims. (Cl. 123—188)

The object of my invention is to provide an internal-combustion engine of simple, durable and inexpensive construction which is especially suitable for automobile use.

5 A further object of my invention is to provide an internal-combustion engine having overhead valves and camshaft and which differs from the conventional motor of this type in that novel means is provided for preventing the oil used to lubricate the camshaft from being drawn into the combustion chambers through the intake valves. To adequately lubricate the camshaft the chamber must be flooded with oil, and when this is done lubricant is invariably drawn down along 10 the intake valve stems to thereby cause excessive oil consumption of the motor. My improved construction corrects this condition.

With these and other objects in view, my invention consists in the arrangement, construction, and combination of the various parts of my improved device, as described in this specification, claimed in my claims, and illustrated in the accompanying drawing, in which:

25 Figure 1 is a side elevation of the upper front portion of my improved engine.

Figure 2 is a sectional view, taken upon the line 2—2 of Figure 1, and

20 Figure 3 is a sectional view, taken upon the line 3—3 of Figure 2.

Before describing the structure of my motor it may be well to note the following facts:

At all throttle openings of the engine the intake valve passageway is under a comparatively high vacuum so that the tendency in all such motors is to draw the oil which lubricates the intake valve stems into the intake passageways. I have overcome this tendency by providing a chamber or pocket in the intake valve stem bushing intermediate of its ends through which the stem extends and conducts gases under pressure from the exhaust passageways to these chambers. In this way the valve stem bushings are under a positive pressure rather than under a vacuum as heretofore has been invariably the case.

Referring to the accompanying drawing, I have used the reference numeral 10 to indicate a conventional cylinder block, which block is provided with a plurality of cylinder bores 11 therein, in which pistons 12 are reciprocally mounted. The engine crankshaft and other associated parts will not be described as they form no part of this invention. Although I have shown an in-line motor it may be well at this point to mention that 50 the invention described herein is equally appli-

cable to V-type motors, radial motors or single cylinder motors.

An overhead camshaft type of cylinder head 13 is detachably secured over the upper end of the cylinder block 10, this head having a plurality of 5 combustion chambers 14 formed therein, one over each of the cylinder bores 11. A camshaft 15 is rotatably mounted in the upper portion of the head 13 in position lengthwise therealong. It will be noted from Figure 2 that a wall 16 extends 10 transversely across the head 13, which wall is spaced above the combustion chambers 14. The space between the wall 16 and the bottom of the head forms a water jacket 17. A second wall 18 extends transversely across the head between wall 15 16 and the top of the head. The space between the wall 18 and the top of the head forms a chamber in which the camshafts rotate and is normally flooded with oil to lubricate the valve tappets while the space between the walls 18 and 16 forms 20 a chamber in which the valve springs are located. In order to give access to the valves, springs, and camshaft and also to facilitate the casting of the head, the side walls of the head between the wall 16 and the top of the head are formed as removable plates 19 and 20, respectively. These plates are secured over the sides of the cylinder head by means of cap screws 21, suitable gaskets being interposed to form an oil-tight seal between the plates and the cylinder head.

From the foregoing it will be seen that three longitudinally extending chambers are formed in the head casting, each separate from the other, the top chamber forming a housing in which the camshaft rotates, while the intermediate chamber 35 forms a valve spring chamber and the lower chamber forms the water jacket for the cylinder head.

A pair of valve openings extends through the upper wall of each combustion chamber 14 and openings aligned therewith are provided in walls 40 16 and 18. In each of the openings in the wall 18 I have provided an inverted cup-shaped tappet 22 which tappets are reciprocally mounted in suitable bearings formed in this wall. In each of the openings in the wall 16 a longitudinally split 45 valve stem bushing 23 is inserted. Conventional valves 24 are reciprocally mounted in each bushing 23, each valve having a head associated therewith which coacts with the surface of the combustion chamber to form a valve seat. A foot 50 25 is formed on each valve, which foot bears against the bottom of the tappet 22 and a valve spring 26 is compressed between a suitable shoulder on each bushing 23 and the adjacent foot 25 so as to resiliently urge the valve foot upwardly 55

against the tappet and thereby urge the tappet against a camshaft 15.

An exhaust valve is illustrated in Figure 2 from which it will be noted that an exhaust passageway 27 is cast in the water jacket 17 and extends from above the valve head out to one side of the cylinder head. An exhaust manifold 28 is fixed to the side of the motor and connects the several exhaust ports 27 with a common exhaust pipe, not shown in the drawing. A suitable intake manifold 29 is provided which is connected by means of an adapter 30 with a carburetor, not shown. The exhaust valve of one cylinder is placed adjacent to the exhaust valve of the next cylinder and likewise the intake valves are paired so that the intake manifold need only have passageways connecting each pair of adjacent cylinders. Each exhaust passageway 27 in like manner conducts the exhaust gases from two adjacent cylinders. 20 In the drawing I have designated the exhaust valves by numeral 24 and although the intake valves are identical with the exhaust valves, for the sake of clearness, I have numbered the intake valves 31. In like manner the numeral 23 is applied only to the exhaust bushing, the intake valve bushing being given the numeral 32.

It may be well to mention that in the applicant's motor the valve stem bushings 23 are machined with sufficient clearance that they may be freely inserted into or withdrawn from the cylinder head. The bushings are retained in place by the method described in United States Patent 1,975,837. For this reason the bushings may not be pressed into the cylinder head because of this method of retaining same in place. An oil-tight seal between the bushings 23 and the head cannot be commercially maintained, due to the above-mentioned clearance, and consequently, the vacuum in the intake manifold 29 in the past has caused oil to be drawn into the manifold through the space around the bushings 23.

The function of this improvement is to prevent oil from being drawn into the intake manifold from around the valve bushings as well as from around the valve stems.

The bushings 23 and 32 are each provided with an annular external groove 33 extending there-around, which grooves lay within the openings in the wall 16 so that the groove and wall forms an annular chamber within the periphery of each bushing. A notch 34, is cut in each exhaust bushing 23 to form a port from the passageways 27 to the exhaust grooves 33. The intake valve bushings 32 do not have this notch formed there-in.

It will be noted that the center portion of the bushings 23 and 32 are relieved to form an annular pocket or chamber 36 around the intermediate portion of the valve stem. A port 35 is drilled in each of these bushings from the bottom of the groove 33 into the chamber 36 so that gas which may be conducted under pressure into the chambers 33 will flow through the ports 35 and exert its pressure within the chamber 36.

Means will now be described whereby exhaust gas will be conducted to the chambers 36 within the intake valve bushings. An outwardly opening groove 37 is cast in the outer wall of the cylinder head 13 in position to be covered by the plate 19. When the plate 19 is secured in position the groove 37 forms a longitudinally extending conduit along the cylinder head. Passageways 38 are drilled from the bottom of the groove 37 so as to intersect the bushing receiving bores in the wall 16 in axial alignment with the

groove 33 in the exhaust valve bushing. Likewise, drilled passageways 39 extend from the bottom of the groove 37 to similar positions with regard to the intake valve bushings. Thus, when the cover 19 is in position a closed passageway is formed from the annular chambers 33 of the exhaust valves through the drilled holes 38, passageway 37 and through the opening 39 to the chambers 33 in the intake valve bushings.

During the normal operation of the motor the exhaust passageways 27 are under the pressure of the exhaust gases as they leave the cylinders. This varies from three to ten pounds per square inch depending upon the muffler used and other factors. This relatively high pressure is due to the friction in the exhaust manifold and the back pressure created by the muffler. Because of the exhaust gas pressure a small portion of the exhaust gas will flow through each of the notches 34 into the annular chambers 33 around the exhaust valve bushings 23 from which the gas will flow through the opening 38 into the longitudinally extending groove 37. Because the exhaust impulses overlap considerably, the groove 37 will be under a relatively constant pressure, as all of the exhaust passageways discharge into this groove. The gases will then flow through the openings 39 into the annular chambers 33 around the intake valve bushings 32. The gases will then flow through the ports 35 in these bushings and enter the chamber 36 around the valve stems. Thus, each of the pockets or chambers 36 around the intake valve stems is under the average pressure within the passageways 27. Consequently, the normal vacuum within the intake manifold can only draw gas from the chamber 36 down around the intake valve stem. The oil which invariably collects around the upper end of the valve stems is not drawn down into the chambers 36 but, if anything, is forced outwardly from these chambers by the exhaust gas pressure, the oil which might be drawn down around the outside of the bushings 23 is also forced upwardly. The upper portions of the valve stems are located in an oil vapor so that when the valves reciprocate in and out of the bushings, the valve stems secure adequate lubrication.

The principal advantage of this construction is the reduced oil consumption of the motor. This is accomplished without maintaining excessively close fits between the valve stems and the valve bushings or between the bushings and the cylinder head. This construction has advantage over motors in which close fits are maintained because such fits do not allow for overload of the motor. If for any reason the motor is overloaded the valves get considerably hotter and, of course, expand. When close fits are maintained this expansion is often sufficient to cause binding between the bushings and the valve stems. This results in scored valve stem bushings with the resultant inefficient operation. With my improved construction, adequate clearance may be provided between the valve bushings and the valve stems and between the bushings and the cylinder head and still the oil which would normally be drawn into the intake passageway is prevented from so being consumed.

A commercial advantage of this construction is that all of the ports 38 and 39 extend parallel to each other, so that they may all be drilled at one time on a multiple spindle drill. The provision of the groove 37 does not require any extra machining as it is cast in place, while the de-

tachable plate 19 must be provided in any event. Some changes may be made in the arrangement, construction and combination of the various parts of my improved device without departing from the spirit of my invention and it is my intention to cover by my claims such changes as may reasonably be included within the scope thereof.

I claim as my invention:

10 1. In an internal-combustion engine, an intake valve having a valve stem associated therewith, said valve stem being reciprocably mounted in a suitable bearing in said engine, said bearing extending into an intake passageway in said engine, which passageway is normally under a substantial vacuum, said bearing having an enlarged chamber formed therein intermediate of its ends through which said stem extends said chamber being closed when said valve stem is in said bearing, and means for introducing gas under pressure in said closed chamber, for the purpose described.

20 2. In an internal-combustion engine, an intake valve having a valve stem associated therewith, an intake valve bushing extending into an intake passageway in said engine, which passageway is normally under a substantial vacuum, said bushing having a chamber associated therewith through which said valve stem extends said chamber being closed when said valve stem is in said bearing, and means for introducing gas under pressure in said closed chamber, for the purpose described.

30 3. In an internal-combustion engine, intake and exhaust valves associated with said engine, said valves communicating respectively with intake and exhaust passageways in said engine, said valves each having a stem associated therewith, which stems are reciprocably mounted in suitable bearings in said engine, there being a chamber associated with the intake valve bearing in axial alignment therewith through which said intake valve stem extends, and means for conducting gases from said exhaust passageway to said chamber, for the purpose described.

40 4. In an internal-combustion engine, intake and exhaust valves associated with said engine, said valves communicating respectively with intake and exhaust passageways in said engine, said valves each having a stem associated therewith, valve bushings in said engine in which said stems are reciprocably mounted, the bushing associated with said intake valve having a chamber formed therein intermediate of its ends through which said intake valve stem extends, and means for conducting gases from said exhaust passageway to said chamber, for the purpose described.

50 5. In an internal-combustion engine, intake and exhaust valves associated with said engine, said valves communicating respectively with intake and exhaust passageways in said engine, said valves each having a valve stem associated therewith, said valves being reciprocably mounted upon said stems in said engine, the portion of said engine which reciprocally supports the intake valve stem having a chamber formed therein through which said intake valve stem extends, and means for conducting gases from said exhaust passageway to said chamber, for the purpose described.

60 6. In an internal-combustion engine, intake and exhaust valves associated with said engine, said valves communicating respectively with intake and exhaust passageways in said engine, said valves each having a valve stem associated

therewith, valve bushings in said engine in which said stems are reciprocably mounted, the bushing associated with said intake valve having its bore enlarged intermediate of its ends so that said stem extends through said enlarged bore, and means for conducting gases from said exhaust passageway to said enlarged bore, for the purpose described.

7. In an internal-combustion engine, a cylinder head, said head having a pair of valve bushings 10 associated therewith, intake and exhaust valves, said valves having valve stems formed integrally therewith which are reciprocably mounted in said valve bushings, the bushing associated with said intake valve having an enlarged bore intermediate of its ends and a passageway extending through said head from said exhaust passageway to said enlarged bore, for the purpose described.

8. In a multi-cylinder internal-combustion engine, intake and exhaust valves for said engine, said valves communicating respectively with intake and exhaust passageways in said engine, said valves each having a valve stem associated therewith, valve bushings in said engine upon which 25 said valve stems are reciprocably mounted, the bushings associated with said intake valves each having a chamber formed therein intermediate of its ends through which the associated intake valve stem extends, said engine having a closed 30 passageway therein extending longitudinally therealong, and branch passageways extending from said main passageway to each of said chambers and to each of said exhaust passageways, whereby gases from said exhaust passageways 35 will be conducted to said chambers, for the purpose described.

9. In a multi-cylinder internal-combustion engine, a cylinder head, intake and exhaust valves in said head, said valves communicating respectively with intake and exhaust passageways in said head, said valves each having a valve stem associated therewith, valve bushings in said head upon which said stems are reciprocably mounted, the bushings associated with said intake valves 40 each having a chamber formed therein intermediate of its ends through which the associated intake valve stem extends, and a passageway through said head from each of said exhaust passageways to the chamber formed in the adjacent intake valve bushing, for the purpose described.

10. A multi-cylinder internal-combustion engine comprising, a cylinder head having a plurality of combustion chambers formed therein, a 55 camshaft rotatably mounted in said head, a pair of vertically spaced transversely extending walls in said head, the space between the combustion chamber side of said head and the adjacent wall forming a water jacket for said combustion chambers, and the space between the other wall and the other side of said head forming a housing for said camshaft, and the space between said walls forming a valve spring receiving chamber, a plurality of valve bushings mounted in the wall 60 adjacent to said combustion chamber, valve tappets reciprocably mounted in the other of said walls, valves reciprocably mounted in said bushings, each of said valves having a head which coacts with a suitable seat in said combustion 65 chamber and having a foot which abuts said tappet, compression springs extending between each valve foot and the adjacent valve bushing, each of the bushings associated with said intake valves having an enlarged chamber intermediate 70

75

of its end, and passageways formed in said head connecting the adjacent exhaust passageways with said enlarged chambers, for the purpose described.

- 5 11. In a multi-cylinder engine, a cylinder head associated with said engine, intake and exhaust valves, said valves communicating respectively with intake and exhaust passageways in said head, said valves each having a valve stem associated therewith, valve bushings in said engine, in which said stems are reciprocally mounted, the bushings associated with said intake valves each having a chamber formed therein intermediate of its ends through which the intake 10 valve stems extend, a groove cast in said head extending longitudinally therealong, said valve bushings each having an annular groove formed therearound with a port extending from each chamber to the adjacent annular groove, drilled

openings extending through said head from said bushings to said longitudinally extending groove, each of said exhaust bushings having a notch therein extending from its annular groove to the adjacent exhaust passageway, and a detachable 15 plate secured over the outer face of said longitudinally extending groove, so that a continuous passageway is formed from each of said exhaust passageways to the annular chamber associated with the exhaust valve bushings and through said drilled openings into said longitudinally extending groove and from said longitudinally extending groove through the remainder of said drilled openings to the intake valve bushings and thence to the chambers associated therewith, whereby 15 exhaust gases will be conducted to said chambers, for the purpose described.

EUGENE J. FARKAS.
